UNITED STATES PATENT OFFICE.

PETER U. RIESS AND ANNA M. JU. RIESS, OF NEW YORK, N. Y.

MARINE PROPULSION.

SPECIFICATION forming part of Letters Patent No. 656,046, dated August 14, 1900.

Application filed May 18, 1899. Serial No. 717,298. (No model.)

To all whom it may concern:

Be it known that we, PETER ULRICH RIESS and ANNA MARIE JULIE RIESS, of the city of New York, (Williams Bridge, borough of Bronx,) in the county and State of New York, have invented certain new and useful Improvements in Marine Vessels, of which the following is a full, clear, and exact description.

The invention relates to manually-propelled marine vessels; and its object is to provide a new and improved marine vessel which is simple and durable in construction and arranged to have its propelling-gear actuated by one or more persons in a very effective manner and without undue exertion, the construction permitting a convenient reversing whenever desired.

The invention consists of novel features and parts and combinations of the same, as will be fully described hereinafter and then pointed out in the claims.

A practical embodiment of our invention is represented in the accompanying drawings, forming a part of this specification, in which similar characters of reference indicate corresponding parts in all the views.

Figure 1 is a longitudinal sectional elevation of the improvement. Fig. 2 is a sectional plan view of the same on the line 2 2 in Fig. 1. Fig. 3 is an enlarged sectional side elevation of the propelling-gear.

The boat A, on which the improvement is applied, is provided with a hold or open central space A' for the accommodation of the occupants and the location of the propelling-gear, and near the bottom of the hold A' is arranged a longitudinally-extending propeller-shaft B, carrying at its rear outer end a propeller C, and on a portion of a shaft within the boat is arranged a sleeve D, journaled in suitable bearings E, bolted or otherwise fastened to the bottom of the boat A. On the sleeve D is secured one, two, or more worms F, each in mesh with a worm-wheel F', secured on a transversely-extending crank-shaft G, carrying crank or pedal arms G' and journaled in bearings held on brackets G², secured to the bottom of the hold A' and supporting-seats G³ for the operator, to permit the latter to conveniently actuate the pedal-arms with his feet to impart a rotary motion to the shaft G.

The rotary motion of the shaft G is transmitted by the worm-wheel F' to the worm F, so that the sleeve D is rotated.

In order to transmit the rotary motion of the sleeve D to the propeller-shaft B, we provide the following mechanism: On the forward end of the sleeve D is secured a bevel gear-wheel H, in mesh with a bevel-pinion H', secured on a vertically-disposed short shaft I, set with its lower pointed end in a step E', carried by a bracket or bearing E², secured to the bottom of the boat. The upper end of the shaft I is countersunk to be engaged by a center I', screwing in a nut I², secured to a seat A⁸, extending transversely in the boat and attached to the sides thereof. On the shaft I, directly under the seat A⁸, is secured a fly-wheel J, and on the lower end of said shaft is fastened a bevel gear-wheel K, adapted to be engaged by either of the bevel gear-wheels L or L', located at opposite sides of the bevel gear-wheel K and secured to the shaft B. On the shaft B is formed an annular shifting-collar B', engaged by a shifting-lever N, connected by a link N' with the hand-lever N² under the control of the operator, to impart a sliding motion to the shaft B and the gear-wheels L L' to move either of the said gear-wheels in mesh with the bevel gear-wheel K.

Now the rotary motion of the sleeve D is transmitted by the gear-wheel H to the pinion H' to rotate the shaft I, and the rotary motion of the latter is transmitted by the bevel gear-wheel K to the gear-wheel L or L' in mesh at the time with said gear-wheel K, and as the gear-wheels L L' are secured on the shaft B it is evident that the latter is rotated, and consequently the propeller C, to propel the boat either forward or backward, according to which of the gear-wheels L or L' is in mesh at the time with the bevel gear-wheel K. A suitable locking device, such as a notched bar N³, secured to the seat A⁸, may be employed to lock the hand-lever N² in the desired position.

It is evident from the foregoing that when the operator or operators actuate the pedal-arms G' a rotary motion is given to the shaft I by the gearing described, and as this shaft I is provided with a fly-wheel J it is evident

that a steady uniform motion is transmitted to the propeller-shaft B to properly rotate the same.

We do not limit ourselves to the special construction shown and described for shifting the bevel gear-wheels L L', as other means may be used, if desired. The fly-wheel J is preferably located under the seat A⁸ to be out of harm's way.

10 In front of each seat G³ is arranged a suitable handle-bar G⁴, adapted to be taken hold of by the operator for his convenient support on the seat G³, and one of the said handle-bars is preferably made to turn and is connected 15 with the ropes or chains of the rudder or steering-gear, so that one of the operators can manipulate the steering-gear without interrupting the work of propelling the vessel with his feet.

20 Having thus described our invention, we claim as new and desire to secure by Letters Patent—

1. A manually-propelled gear for marine vessels, comprising a propeller-shaft, a sleeve 25 through which passes said shaft, a foot-actuated driving-gear for said sleeve, and a gearing between said sleeve and said propeller-shaft, substantially as shown and described.

2. A manually-propelled gear for marine vessels, comprising a propeller-shaft, a sleeve 30 through which passes said shaft, a foot-actuated driving-gear for said sleeve, a gearing between said sleeve and said propeller-shaft, and comprising a bevel gear-wheel on the sleeve, a bevel-pinion in mesh with said bevel gear-wheel, a fly-wheel shaft carrying said pinion, a bevel gear-wheel on said fly-wheel shaft, and two gear-wheels mounted to turn with the said propeller-shaft, and adapted to be moved into and out of mesh with the gear-wheel on said fly-wheel shaft, substantially as shown and described. 35

3. A manually-propelled gear for marine vessels, comprising a pedal-actuated crank-shaft, a worm-wheel on said shaft, a worm in 45 mesh with said worm-wheel, a sleeve carrying said worm, a propeller-shaft extending through said sleeve, and a gearing between said sleeve and said propeller-shaft, substantially as shown and described.
